UNITED STATES PATENT OFFICE.

CLARENCE W. COLLEGE, OF HOPEWELL, PENNSYLVANIA.

FILM-WASHER.

1,146,136.

Specification of Letters Patent. Patented July 13, 1915.

Application filed February 4, 1915. Serial No. 6,014.

To all whom it may concern:

Be it known that I, CLARENCE W. COLLEGE, a citizen of the United States, residing at Hopewell, in the county of Bedford and State of Pennsylvania, have invented certain new and useful Improvements in Film-Washers, of which the following is a specification.

My invention relates to improvements in film washers, the invention being particularly designed and adapted for use in properly supporting and washing photographic films, and the like.

The primary object of the invention is to provide a generally improved device of this class of exceedingly simple, cheap, and efficient construction, adapted to receive and securely hold films of varying dimensions and lengths and at the same time properly wash the films while being held.

A further object is the provision of a film washer having improved means for receiving and discharging the liquid, said discharging means being in the form of an adjustable valve or gate whereby to regulate the flow of the liquid through the washer and over the film being treated.

A still further object is the provision of improved removably and adjustably mounted film clamping members adapted to be readily attached to or detached from the ends of the film whereby the latter may be readily inserted in or removed from the film washer as well as adjusted therein as desired.

With the above mentioned and other ends in view, the invention consists in the novel construction, arrangement, and combination of parts, hereinafter described, illustrated in one of its embodiments in the accompanying drawings; and particularly pointed out in the appended claims.

Referring to the drawings, forming a part of this specification, Figure 1, is a top plan view of a film washer, showing the film inserted and clamped therein preparatory to being washed. Fig. 2, is a cross-sectional view taken on line 2-2 of Fig. 1.

Similar numerals of reference designate like parts throughout all the figures of the drawings.

The improved film washer comprises a base or bottom 1, carrying spaced helicoidal walls 2, said walls being vertically arranged and extending upwardly from the base or bottom and terminated in a common hori-

zontal plane so that the coils or convolutions thereof form a complete helicoid with an intervening space of like form.

The lower edges of the walls 2, are suitably secured or soldered upon the base or bottom 1, and as a means of further reinforcing the latter as well as the outer peripheral coil of the helicoid, the outer edge of the bottom is provided with an upwardly extending flange 1^a, spaced slightly beyond the base portion of the outer coil or convolution of the helicoid, said upwardly extending flange being adapted to receive and interlock with a hooked flange 3^a, of a depending supporting ring 3, the latter terminating in a friction bearing beading 3^b, forming a reinforcing base for the washer as a whole and also forming a further support and means of attachment for the outer coil or convolution of the helicoid 2.

The helicoid 2, is provided with axially and circumferentially located liquid receiving and discharging portions 4 and 5, respectively, said liquid receiving portion 4, in the present instance being in the form of a receiving head or pipe adapted to be suitably connected to a suitable source of fluid supply, as for example,—through the medium of a hose section (not shown) communicating with a faucet, or the like, and the liquid discharge portion 5, in the present instance, is in the form of a discharge valve or gate, formed, in the present instance, by means of an adjustably mounted spring valve member 5^a, suitably connected to one of the coils or convolutions of the helicoid and extending outwardly in close proximity to the outer terminating portion of the helicoid, forming a vertically extending fluid discharge recess 5^b, through which the fluid is adapted to discharge, and as a means of regulating the valve opening or recess 5^b, thereby regulating the flow of the liquid in its helicoidal course between the walls of the helicoid 2, an adjusting bolt or screw 6, is mounted in a threaded reinforcement 2^a, and is adapted to bear against the free end of the spring valve member 5^a, the latter being provided with a reinforcement 5^c, and the bolt being provided with a winged head 6^a, for convenience in adjusting the valve member 5^a, in an obvious manner.

As a means of readily inserting a film 7, into or removing the same from the improved film washer, as well as securely holding and adjusting the same between the

walls of the helicoid, suitable film holding or clamping members 8, are provided, said holding or clamping members being removably and adjustably mounted between the 5 convolutions of the helicoid and each consisting, in the present instance, of a single length of metal bent upon itself midway between its ends to form a vertically extending film holding clamping loop 8, open at 10 its top and terminating in depending spring members 8^a, adapted to bear against the adjacent walls of the helicoid and to frictionally support the clamping members in any 15 desired position. By reason of the construction described, it is apparent that the film holding clamping loops 8, will securely clamp and hold the ends of the film between the walls of the helicoid and that the stream of liquid issuing from the liquid receiving 20 portion or head 4, will be divided at the inner end of the film as held by the clamping member and will be caused to traverse opposite sides of the film in two streams.

From the foregoing description, taken in 25 connection with the accompanying drawings, the operation and advantages of my invention will be readily understood.

Having thus described one of the embodiments of my invention, what I claim and desire to secure by Letters Patent, is,

1. In a film washer, a plurality of film holding members each comprising a single length of metal bent midway of its ends forming a vertically extending film holding and clamping loop terminating in depending spring members.

2. In a film washer, a helicoid made up of a plurality of spaced members, a bottom

secured to the members of said helicoid and provided with an upwardly extending flange 10 in proximity to the outer member of said helicoid, and a supporting ring provided with a hooked flange engaging said upwardly extending flange and abutting against said outer member of said helicoid 45

3. In a film washer, the combination with a bottom carrying a plurality of spaced vertically extending convolutions arranged in the form of a helicoid, of film holding and clamping loop members removably and adjustably mounted between the walls of said helicoid. 50

4. In a film washer, a film holding and clamping device comprising a single length of metal bent midway of its ends into a film 55 holding and clamping loop open at its top and terminating in depending spring members arranged on the opposite sides of said loop.

5. In a film washer, the combination with a helicoid having spaced convolutions, and a bottom connected to said helicoid provided with an upwardly extending flange spaced from and affording a recess about the base portion of the last or outer convolution of 60 said helicoid; of a supporting ring provided with a hooked flange taking over said upwardly extending flange and seated in said recess.

In testimony whereof I have affixed my 70 signature in presence of two witnesses.

CLARENCE W. COLLEGE.
